UNITED STATES PATENT OFFICE.

JOHN W. MEALY, OF MOUNT WASHINGTON, MARYLAND.

DESIGN FOR A HANDLE FOR SPOONS OR SIMILAR ARTICLES.

SPECIFICATION forming part of Design No. 31,664, dated October 17, 1899.

Application filed September 12, 1899. Serial No. 730,274. Term of patent 7 years.

To all whom it may concern:

Be it known that I, JOHN W. MEALY, a citizen of the United States, residing at Mount Washington, in the county of Baltimore and State of Maryland, have invented and produced a new and original Design for a Handle for Spoons, Forks, or Similar Articles, of which the following is a specification.

This invention relates to a design for a handle for spoons and similar articles.

The design consists of a handle which is rounded at the top and gradually tapers toward the bowl, having a series of waved grooves 1, being concave in cross-section, arranged around the edge of the handles, a se-

ries of indentations 3, also extending around the handle and near the inner edge of the waved grooves, and a plain center 2, as shown in the accompanying drawing.

Having thus described my invention, what I claim is—

The design for a handle for spoons and similar articles as herein shown and described.

In testimony whereof I affix my signature in the presence of two witnesses.

JOHN W. MEALY.

Witnesses:

ALBERT P. STROBEL,
CHAPIN A. FERGUSON.
